US00D630517S

(12) **United States Design Patent**
Toh et al.

(10) **Patent No.:** **US D630,517 S**
(45) **Date of Patent:** ** *Jan. 11, 2011

(54) **CONTAINER**(75) Inventors: **Kiat Cheong Toh**, Forest Hills, NY (US); **Liam Hawry**, Chicago, IL (US)(73) Assignee: **Colgate-Palmolive Company**, New York, NY (US)(**) Term: **14 Years**(21) Appl. No.: **29/338,294**(22) Filed: **Jun. 9, 2009**(51) LOC (9) Cl. .... **09-01**(52) U.S. Cl. .... **D9/529**; D9/552; D9/558; D9/435; D9/447(58) **Field of Classification Search** D9/500, D9/516, 521, 529-530, 537-543, 549, 550-552, D9/558-561, 563-567, 569-575, 682-694, D9/435, 447, 449; 215/382-384; 220/660, 220/669

See application file for complete search history.

FOREIGN PATENT DOCUMENTS

EM ECD000051883-0015 7/2003

(Continued)

Primary Examiner—Carol Rademaker(74) *Attorney, Agent, or Firm*—Amy M. Fernandez(57) **CLAIM**

The ornamental design for a container, as shown and described.

DESCRIPTION

FIG. 1 is a perspective view of the container of our design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

All broken lines shown in the drawings are for environmental purposes only and form no part of the claimed design.

1 Claim, 6 Drawing Sheets# US D630,517 S
